UNITED STATES PATENT OFFICE

AUGUST SCHAFER, OF COLUMBUS, OHIO

HERNIAL TRUSS

Application filed October 25, 1929. Serial No. 402,525.

This invention relates to trusses for ruptures, especially those involving a protrusion of the intestine, and the object of the invention is to provide an improved construction whereby the truss is more securely supported in its place, and without the necessity of a leg strap especially for persons of sedentary habits and who do no heavy lifting. Other objects will appear from the disclosure herein.

The invention is embodied in the example herein shown, the features of novelty being finally claimed.

In the accompanying drawing—

15 Figure 1 is a front view of the device according to the invention.

Fig. 2 is a view of the pad member looking at the lower edge of that member as seen in Fig. 1.

20 Fig. 3 is a vertical section on the line III—III Fig. 1.

Fig. 4 is a view of the rear face of the pad proper removed from the frame plate.

25 In the views 5 designates the frame which is a thin metallic plate upon which is riveted a rather hard rubber foundation 6. The lower portion of the plate 5 is bent rearward where it is built up with pieces of leather 7 or other suitable material to afford a supporting face that is compoundly curved as best seen at 7^a Fig. 2. Upon the surface 7^a is secured a pad 8 called a supplemental pad of sponge rubber the curve of the lower edge of which conforms to the curve of the supporting face 7^a, said edge projecting slightly below the edge of the supporting face and conforming to the pubic portion of the pelvic bone.

40 The frame near its central portion is provided with a vertical slot 9 through which is inserted from the front side a screw 10 or pin-like member adapted to engage at its inner end a button 11; and on said screw 10 is a washer 12 sliding with said screw. Between said button and the washer 12 is a coil spring 13 tending to hold the button 11 pressed and projecting rearward toward the body of the washer. The screw 10 with its said appurte- 45 nances is movable up and down in the slot 9; and said parts also may have a slight uni-

versal movement. This capacity of the screw facilitates the application and removal of the pad proper which will now be described.

The character 14 designates said pad, it being preferably made of sponge rubber. Said pad is provided at its forward side with a central socket 15 so that it can be sprung onto the button, or removed therefrom, at will and be placed in substantially the position in Fig. 60

3. The upper portion of the pad, at its forward side, is made with an arcuate recess 16 around the socket and spaced therefrom so as to make that portion of the pad somewhat more yielding than otherwise to pressure. 65

The pad 8 can be called the supplemental or supporting pad because it is designed to prevent downward displacement of the truss, its lower edge being designed to conform generally to the upper surface of the pubic portion of the pelvic bone while the pad proper 15 operates to hold the intestine up. Because, in use, the pad 8 is lodged above the pubic bone the truss is held from descending from its proper place. 70

To hold the pad to the body after its adjustment thereto and to draw the lower pad inward over the pubic bone the plate 5 is provided with lateral hooks 17 set at an incline to the plate to which the opposite ends 18 of a body strap are attached as shown in Fig. 1. Said body strap is provided with the usual buckles for holding it as tight as necessary to keep the pad in proper position. 75

If the patient does heavy lifting one end 80 of a leg strap can be attached to a pin 20 on the plate 5 and pinned or otherwise secured to the rear of the body strap.

The truss shown is for a rupture at the right hand side. For the left hand side the curve of the supporting pad 8 is merely the reverse of that shown so as to fit above the pubic bone at the left hand side. Otherwise the parts can be identical but the forms of the parts can be changed without departing 95 from the gist of the invention as claimed.

What I claim is:

1. A hernial truss including a plate having an inwardly bent and downwardly inclined lower portion, a pad proper yieldingly 100

and slidingly supported for vertical movement on the upper portion of said plate; and a supplemental pad rigidly supported on the lower bent portion of said plate said pad being horizontally elongated to rest above and be supported by the pubic bone of the wearer.

2. A hernial truss including a plate having an inwardly bent and downwardly inclined lower portion, a pad proper yieldingly and slidingly supported for vertical movement on the upper portion of said plate; and a supplemental pad rigidly supported on the lower bent portion of said plate, said pad being horizontally elongated and having its bearing face inclined downwardly toward the body of the wearer, and adapted to rest above, and be supported by, the pubic bone of the wearer.

AUGUST SCHAFFER.
